UNITED STATES PATENT OFFICE.

WILLIAM T. HOGARTH AND DANIEL K. DEAL, OF WILLIAMSPORT, PENNSYLVANIA.

TOOL FOR CLEANING BOILER-HEAD CAP-SEATS.

1,026,442.

Specification of Letters Patent.

Patented May 14, 1912.

Application filed May 5, 1911. Serial No. 625,160.

To all whom it may concern:

Be it known that we, WILLIAM T. HOGARTH and DANIEL K. DEAL, citizens of the United States, and residents of the city of 5 Williamsport, county of Lycoming, and State of Pennsylvania, have invented certain new and useful Improvements in Tools for Cleaning Boiler-Head Cap-Seats, of which the following is a specification.

10 Our invention relates to tools for cleaning the cap seats on the boiler heads of water tube boilers.

In water tube boilers the tubes are arranged with their ends secured in the tube sheets of the headers. Directly opposite the ends of the tubes the boiler heads or hand hold plates are provided with hand holes which are closed by hand hole caps. To make tight joints between the caps and boiler 20 head or hand hole plate, either ground joints are provided or gaskets are interposed between the caps and the plate. In either case, when the caps are to be reset, it is necessary to thoroughly clean the plates 25 by removing all traces of the old gaskets or by scraping the ground joints, as the case may be. It is a difficult task to remove the gaskets which have hardened on the plates and to clean the ground joints which have 30 become incrusted, in order to permit tight joints to be made between the caps and the plates when the former are reset.

The object of our invention is to provide a tool for removing the old gaskets and for scraping the ground joints above mentioned.

A further object of our invention is to provide a device of the class mentioned which shall be of simple construction, strong 40 and durable and which may be readily operated.

Other objects will appear hereinafter.

With these objects in view our invention consists generally in a rod or stem, a 45 scraper fixed transversely of said stem, a slide on said stem, means for clamping said slide and said scraper upon opposite sides of a hand hole plate or boiler head and means for turning said stem.

50 Our invention further consists in various details of construction and arrangements of parts all as will be fully described hereinafter and particularly pointed out in the claims.

55 Our invention will be more readily un-

derstood by reference to the accompanying drawings forming a part of this specification and in which—

Figure 1 is a side elevation of a tool embodying our invention in its preferred form, 60 Fig. 2 is a longitudinal section through the same, and Fig. 3 is a detail plan view of the knife or scraper.

Referring now to the drawings A indicates a hand hole plate or boiler head of a 65 water tube boiler and B one of the hand holes therein to give access to a tube and which is closed by a cap.

The tool comprises a stem 1, a scraper or knife 2, a slide 3 and a clamping member 4, together with suitable means for rotating the stem. The stem 1 is threaded as at 5 throughout the greater portion of its length and one end thereof is squared as at 6 to receive a crank 7 or other suitable means for 70 rotating the same. The scraper 2 is threaded upon the opposite end of the stem and comprises a transverse bar 8 and a pair of off-set knives 9 at the ends thereof. The knives are preferably inclined in opposite 75 directions from the axis of the bar 8 and also to the axis of the stem 1, as illustrated in Fig. 3. 10 indicates a lock or jam nut for clamping the scraper 2 against rotation on the stem 1. 85

The slide 3 consists of a circular member or disk of greater diameter than the apertures B of the plate A and provided upon its face adjacent the scraper with an extension portion 11 concentric therewith and adapted to extend within the aperture 2. The opposite side of the slide is provided with a convex extension 12 terminating in a flat face or seat 13, surrounding the stem 1, the purpose of which will appear hereinafter. 90

14 indicates a centrally disposed bore extending through the member 3 of sufficient diameter to receive the stem 1 and permit said member to slide free thereon, and 15 indicates a key carried by the member or 100 slide 3 and engaging a key way 16 extending longitudinally of the stem 1.

The clamping member 4 comprises a transverse member 17 centrally tapped as at 18 to receive the stem or screw 1 and angularly disposed arms 19 extending substantially parallel to the stem terminating in well rounded ends or knobs 20. It is obvious that by turning the member 4 in one direction the slide 3 will be forced toward 110

the scraper and that the tube sheet of the boiler may be clamped between the same as shown in Fig. 2. Suitable means are provided for retracting the slide 3 as the 5 clamping member 4 is turned in the opposite direction. To this end the member 4 is provided with a pair of arms or extensions 21, the ends of which are turned inwardly as at 10 22 to engage a peripheral groove 23 formed in the slide 3.

In using the device the end with the knife or scraper is inserted through the aperture B. This may be readily done after retracting 15 the members 3 and 4 sufficiently, by inserting one end of the scraper first. The clamping member 4 is then turned until the slide 3 engages the plate A and the knife or scraper drawn into close contact with the opposite face of the plate. The stem 1 is 20 then rotated by means of the crank 7 or other means provided for the purpose. This will cause the member 3 and scraper 2 to rotate therewith, the latter cleaning the gaskets off of the plate or scraping the 25 ground surface as the case may be. As the work progresses the scraper may be tightened against the plate by turning the member 4 slightly. The member 4 engages the 30 seat 13 on the member 3 and as there is nothing to hold the member 4 it turns with the slide 3, thus maintaining a constant distance between the slide and scraper except when the clamping member 4 is intentionally turned.

35 Having described our invention what we claim as new and desire to secure by Letters Patent is:

1. A tool of the class described, comprising a stem, a transverse scraper fixed thereto, a slide keyed to said stem and provided 40 with an extension to engage in a hand hole in a boiler head and a clamping member

threaded on said stem and adapted to engage said slide.

2. A tool of the class described, comprising a stem, a transverse scraper fixed thereto, a slide on said stem, a clamping member 45 threaded on said stem and adapted to engage said slide, means for clamping said slide and said scraper against opposite sides of a boiler head and means for turning said stem.

3. A tool of the class described, comprising a stem, a transverse scraper fixed thereto, a slide upon said stem provided with an 50 annular recess, a clamping member threaded on said stem and engaging said slide, arms connected to said slide and engaging in said recess and means for turning said stem.

4. A tool of the class described, comprising a stem provided with a longitudinal slot, a transverse scraper upon said stem, a slide on said stem provided with a key engaging in said slot, said slide having a reduced bearing shoulder on its outer face 55 encircling said stem and an extension on its inner face adapted to engage in a hand hole of a boiler head and also provided with a peripheral groove, a clamping member 60 threaded upon said stem and adapted to engage said bearing shoulder, angularly disposed arms on said clamping member substantially parallel with said stem, extensions 65 fixed to said arms and having their ends turned to engage said peripheral groove, 70 and means for turning said stem.

In testimony whereof we have signed our names to this specification in the presence of subscribing witnesses.

WILLIAM T. HOGARTH.
DANIEL K. DEAL.
